(57) **CLAIM**

The ornamental design for a stylus pen for hand-held electronic game machine, as shown and described.

DESCRIPTION

FIG. 1 is a front, top and right perspective view of a stylus pen for hand-held electronic game machine showing our new design;

FIG. 2 is a rear, bottom and left perspective view thereof; FIG. 3 is a front elevational view thereof, a rear elevational view being a mirror image thereof;

FIG. 4 is a top plan view thereof;

FIG. 5 is a bottom plan view thereof;

FIG. 6 is a left side view thereof; and,

FIG. 7 is a right side view thereof.
